UNITED STATES PATENT OFFICE.

JAY B. RHODES, OF CHICAGO, ILLINOIS, ASSIGNOR TO FREDERICK C. AUSTIN,
OF SAME PLACE.

STEAM OR OTHER FLUID ACTUATED VALVE.

SPECIFICATION forming part of Letters Patent No. 639,288, dated December 19, 1899.

Application filed March 10, 1898. Serial No. 673,315. (No model.)

To all whom it may concern:

Be it known that I, JAY B. RHODES, a citizen of the United States, residing at Chicago, in the county of Cook and State of Illinois, 5 have invented a certain new and useful Improvement in Steam or other Fluid Actuated Valves, of which the following is a specification.

My invention while particularly applicable 10 to steam or other motive-fluid actuated pumps is also adapted for other service where steam or other motive-fluid actuated pistons are required.

The objects of my invention are to avoid 15 exhausting through the piston-stem and to dispense with a multiplicity of stuffing-boxes in connection with a valved piston having a longitudinally-arranged exhaust-port controlled by a slide-valve, to provide for a free 20 exhaust, to relieve the valve from opposing pressure, to secure highly-efficient action, and to provide certain novel details, as herein-after set forth.

In the accompanying drawings, Figure 1 25 shows the piston-cylinder in side elevation. Fig. 2 is a section taken centrally and longitudinally through the piston-cylinder and shows in outline a pump which can be operated by the piston. Fig. 3 is a section taken 30 centrally and longitudinally through the piston-cylinder and a portion of the length of the piston on a larger scale, the plane of the section being at right angles to the plane of Fig. 2. Fig. 4 is a section taken centrally and 35 longitudinally through the piston-cylinder and piston on a plane at right angles to the plane of Fig. 3. Fig. 5 is a section on line $x-x$, and Fig. 6 is a section on line $y-y$, in Fig. 3. Fig. 7 is a plan view of the piston and a section 40 taken through the valve-carrier on line $z-z$ in Fig. 5. Fig. 8 is an enlarged perspective view of the valve. Fig. 9 is a section on line $z'-z'$ in Fig. 7. Fig. 10 is a section taken longitudinally through the piston, valve, and 45 valve-carrier on line $z''-z''$ in Fig. 5. Fig. 11 is a perspective view of the piston on a larger scale. Fig. 12 is a perspective view of the valve-carrier.

The piston-cylinder A is provided at a point 50 between its ends with a laterally-arranged inlet-port 1, through which steam or other

fluid-pressure is admitted for the purpose of operating both the piston and a slide-valve employed to control the supply and exhaust. The piston-cylinder is also provided at a point 55 between its ends with a laterally-arranged exhaust-port 2, through which the exhaust is discharged.

The piston B is arranged to reciprocate within the piston-cylinder and is provided at 60 one end with a rod or stem 3, which extends and works through a stuffing-box C at one end of the piston-cylinder.

The piston comprises two main body portions, the one being adapted to provide within 65 the piston-cylinder an annular pressure-space and to afford a seat or bearing for a slide-valve and the other being adapted to provide within the piston-cylinder a comparatively large exhaust-space which is in constant communication with the exhaust-port 2. For such purpose the piston is provided at its ends with heads or circular flanges 4 and 5, and at a suitable point between such heads it is provided with an annular flange 6, which may be 70 termed the "middle" flange. The body portion of the piston between its head 4 and the middle flange 6 is adapted to provide a considerable area of space, which serves as an exhaust space or chamber in constant communication with the exhaust-port 2. On the other hand, the body portion of the piston, between its head 5 and middle flange 6, is adapted to provide a seat or bearing for a reciprocating slide-valve and is suitably reduced in diameter to provide an annular pressure-space which receives fluid-pressure 75 from port 1, as hereinafter more fully set forth.

In order to supply fluid-pressure to the interior of the piston-cylinder at points opposite the heads of the piston and also to exhaust from such points, the piston is provided with longitudinally-extending ports or ducts 7 and 8, which open through its heads 4 and 5 and extend back therefrom to the 80 body portion of the piston between the piston-head 5 and the middle flange 6. These ports open laterally through such body portion of the piston, as illustrated, for example, by Fig. 7, wherein the longitudinally-extending portions of said ports or ducts are indicated by dotted lines. The piston is also pro- 85 90 95 100

vided with a centrally-arranged and longitudinally-extending exhaust port or duct 9, which opens into the exhaust-space between the middle flange 6 and the piston-head 4 and which extends back therefrom and opens through the body portion of the piston correspondingly with the ports 7 and 8 by way of a couple of branch ports 9^a and 9^b. The ports 7 and the branch port 9^a are preferably on a line taken transversely through the piston, and likewise the ports 8 and the branch port 9^b are preferably on a like line, it being understood that while I could employ but one port 7 and one port 8 I prefer to duplicate such ports and to arrange the branch port 9^a between a couple of ports 7 and in like manner to arrange the branch port 9^b between a couple of ports 8. The longitudinally-extending exhaust-port 9, which is thus provided with a couple of lateral branch ports or port openings 9^a and 9^b, takes the exhaust from ports 7 and 8 alternately and delivers such exhaust to the main exhaust-space at one end portion of the piston. As a preferred and simple arrangement for affording a comparatively large area of exhaust space or chamber the head 4 is connected with a circular flange or plate 10 by a couple of comparatively small cylindric or otherwise suitably shaped body portions 11, which are arranged and suitably bored to provide portions of the ports or ducts 7. With such arrangement the plate 10 can be bolted to the middle flange 6 and provided with a central opening in register with and forming part of the central exhaust-port 9, it being observed that the connecting body portions 11 between the head 4 and the plate 10 can be arranged at opposite sides of the center of such plate, so as to leave ample space for the central opening in the latter. Broadly considered, one end portion of the piston is provided with portions of the ports or ducts 7 and is recessed or reduced in diameter, so as to provide a comparatively large area of exhaust-space, which is in constant communication with the exhaust-port 2 and which takes the exhaust from ports 7 and 8 by way of port 9. As a matter of further improvement, however, the piston resembles a double spool or two spools arranged end to end and either integral or more desirably formed separately and secured together, the one spool-shaped part being formed with a body portion 12, through which the several ports open laterally, and the other spool-shaped part being formed with a pair of connecting portions 11, extending between its ends and provided with continuations of the ports or ducts 7. In this way a comparatively large area of exhaust-space can be conveniently formed without undesirably weighting the piston, and at the same time suitably strong connection is afforded between head 4 and one end of the body portion 12 of the piston. Also the exhaust-port 9 can discharge freely and directly into the exhaust-space thus provided.

The slide-valve D is ported with reference to the ports, which open laterally through the piston, and to such end it is provided with a pair of parallel ports or channels 13 and a couple of intervening openings or ports 14, as best shown in Fig. 8. The ports or channels 13 are of such length and are so arranged that at suitable moments one of such ports or channels will come opposite and thereby connect ports 7 with the branch exhaust-port 9^a, and similarly at suitable moments the other one of said ports or channels 13 will come opposite and connect ports 8 with the branch exhaust-port 9^b. In this way the exhaust can be delivered from ports 7 and 8 to the branch exhaust-ports 9^a and 9^b in alternation. During operation the ports 14 of the valve will also register with ports 7 and 8 successively, so as to alternately deliver fluid-pressure from the pressure-space around one portion of the piston alternately to the interior of the piston-cylinder at points opposite the ends of the piston.

The body portion 12 of the piston is preferably made cylindric and provided with a recess or offset having its bottom adapted to form a seat 15 for the slide-valve. This seat may be convex or concave, but I prefer to form it flat. The recess or offset thus formed in the piston is of a length to allow suitable latitude of shift on the part of the valve, which when arranged to slide upon such seat will work between a couple of stops or abutments provided by the end walls 27 of the recess or offset. The valve is operated by a carrier E, (see Fig. 12,) consisting of a part-cylindric sleeve having its ends provided with annular flanges 16. This carrier is fitted to slide back and forth upon the body portion 12 of the piston and serves both as a holder for the valve and as a means for moving the same along the valve-seat, an advantage of such construction being that the valve can be fitted between the flanges of the carrier and caused to suitably bear upon the seat by reason of pressure within the surrounding pressure-space. With such arrangement it will only be necessary to provide such connection between the valve and the carrier as will prevent the valve from working sidewise, a simple expedient being to insert pins or screws 17 through suitably large holes 18 in the valve and then secure such pins or screws in sockets 19, formed in the part-cylindric body portion 20 of the carrier. With such arrangement the valve will be free to move to a limited extent upon the pins or screws 17 in a direction perpendicular to the seat 15. It will therefore be held in sliding contact with the seat regardless of the position of the piston, and hence will automatically take up wear, the result being a slide-valve which is automatically adjustable to take up such wear.

The formation of the recess or offset in the body portion 12 of the piston leaves the same with cylindric ends or end parts 21, respectively at opposite ends of the valve-seat and

respectively extending back from the piston-head 5 and the middle flange 6. These cylindric parts 21 of the piston are provided with ports 22 and 23, arranged to extend from the 5 recess or offset in the piston to and through the cylindric surfaces of the end parts 21 of the body portion 12 of the piston. The valve is also provided with a couple of notches or 10 ports 24 and 25 with reference to the ports 22 and 23 in the piston.

The flanges 16 of the valve-carrier are also fitted to the inner wall of the piston-cylinder, being preferably provided with packing-rings 16^a, by which arrangement an annular pressure-space will be afforded between these 15 flanges of the valve-carrier, and the valve will be subject to pressure within such space.

When the piston is at the left, as shown, and the valve-carrier is at the extreme right, 20 fluid-pressure from port 1 will force its way between the middle flange 6 of the piston and the contiguous or adjacent end flange of the valve-carrier, and thereby shift the valve-carrier to the extreme left, as illustrated, the 25 valve of course being carried by and shifted with the valve-carrier during such movement on the part of the latter. This movement of the valve-carrier will uncover and expose the receiving ends of ports 22 in the piston to the 30 incoming pressure and will also leave a space between one end of the valve and one end wall of the recess or offset in the piston, as in Fig. 4, wherein it will be seen that such space is simply an end portion of the recess in the 35 piston unoccupied by the valve and having as its walls the valve-seat, one end of the valve, one of the end walls 27 of such recess in the piston, and an inner side portion of one of the end flanges of the valve-carrier. Fluid-pressure 40 from ports 22 will therefore enter the temporary space thus afforded by the shift of the valve to the left and will thereupon pass through the passage or port 24 in the valve into the annular pressure-space between the 45 flanges of the valve-carrier. The fluid-pressure from the pressure-space between the flanges of the valve-carrier will thereupon pass through ports 14 of the valve into ports 8 of the piston, and thence to the left-hand 50 end of the latter. The piston will thereupon be driven to the right, with the valve, however, in the same relative position.

During the movement of the piston to the right the exhaust will take place through 55 ports 7 of the piston, thence to the branch exhaust-port 9^a by way of one of the channels or ports 13 in the valve, which at such juncture is in position to place one of its ports 13 over ports 7 and 9^a, and thence through 60 the common exhaust-port 9 to the exhaust-space between head 4 and the middle portion of the piston, from which said exhaust-space the exhaust passes out through the ultimate 65 exhaust-port 2 regardless of the position of the piston.

When the piston reaches the end of its stroke to the right, the valve and piston will

be in position to permit fluid-pressure from port 1 to force its way between head 5 of the piston and the end flange of the valve-carrier 70 contiguous or adjacent to such end flange of the valve-carrier, and thereby permit the valve-carrier and valve to be shifted to the right. When the valve-carrier and valve are to thus shift to the right, it is essential to exhaust 75 from the annular space between the middle flange 6 of the piston and the end flange of the valve-carrier opposite such middle flange of the piston in order to allow the valve-carrier and valve to be shifted, it being 80 observed that while the movement of the piston to the right will bring the annular space between the flanges of the valve-carrier opposite and in communication with the inlet-port 1 pressure will exist in the annular 85 space intervening between the middle flange of the piston and the next adjacent end flange of the valve-carrier. The exhaust from such space between the middle flange of the piston and the next adjacent end flange of 90 the valve-carrier takes place at such juncture directly from said space to the ultimate exhaust-port 2. Thus when the piston is at the right the middle flange 6 of the piston will be opposite the exhaust-port 2, but owing 95 to its conformation said flange will not and cannot close the exhaust-port, which is relatively wider than the width of the annular face of the flange, which contacts with and slides along the inner cylindric wall of the 100 piston-cylinder. In this way the exhaust-port 2 also serves as a port for relieving pressure in opposition to the shift of the valve-carrier and valve in one direction.

When the piston is at the right and the 105 valve has been shifted to the right, fluid-pressure from inlet-port 1 will pass into an annular space temporarily formed between head 5 of the piston and the next adjacent end flange of the valve-carrier. Such fluid-pressure will thence pass through ports 23 of 110 the piston, thence through the notch or port 25 of the valve into the annular space between the end flanges of the valve-carrier, and thence through ports 14 of the valve into 115 ports 7 of the piston, so as to again drive the latter to the left. Simultaneously therewith the exhaust from the left-hand end of the piston-cylinder will take place through ports 8 to the common exhaust-port 9 in the piston 120 by way of one of the channels or ports 13 in the valve and the branch exhaust-port 9^b in the piston. During the movement of the piston to the left the valve-carrier will remain with one of its end flanges contiguous 125 to or close to the middle flange of the piston, and hence there will be an annular space between the piston-head 5 and the next adjacent or directly opposite end flange of the valve-carrier. In order to relieve or exhaust 130 pressure within such space, so as to permit the valve-carrier and valve to be again shifted to the left—as in Figs. 3 and 4, for example—I provide the inner wall of the piston-cylin-

der with a relief groove or channel 26, arranged adjacent to the end of the cylinder, in which way pressure from said space can pass around the piston-head 5 and thence into ports 8.

When the piston is at the left, its head 4 will register with the exhaust-port 2, but will not close the same. With such arrangement there will be a momentary direct exhaust from the right-hand end of the piston-cylinder into the port 2 when the piston is in the position shown in Figs. 3 and 4. This arrangement has a direct relation to the automatically-adjustable valve—that is to say, where the valve is free for adjustment in a direction to take up wear and is maintained in suitable contact with the valve-seat by fluid-pressure regardless of such wear it becomes desirable to momentarily lessen such fluid-pressure, so as to allow the valve to be readily shifted along its seat. When, therefore, the piston is at the left-hand end of its stroke and the valve is at the right, with its ports 14 over the ports 7, fluid-pressure within the annular space between the flanges of the valve-carrier will exhaust through ports 14 and 7 into the space at the right-hand end of the piston-cylinder, and thence into port 2, through a portion of such port not covered by head 4 of the piston. This exhaust will momentarily lessen the pressure on the valve and permit the latter to be readily shifted in the manner hereinbefore described.

When the piston is at the right and the valve is at the left hand end of its play preparatory to shifting the valve for the purpose of reversing the stroke of the piston, pressure upon the valve will also be decreased or exhausted, since at such juncture the exhaust from the annular space between the flanges of the valve-carrier will take place through port 24 in the valve into the temporary space between one end of the valve and an end wall of the recess in the piston, thence through ports 22 into the annular space between the middle flange 6 of the piston and the next adjacent end flange of the valve-carrier, and thence into the exhaust-port 2, through a portion of such port not covered by the piston-flange 6. It will also be seen that while at such juncture ports 14 of the valve will be over ports 8 of the piston a momentary preliminary exhaust from the cylinder at the left of the piston will take place through ports 8 and 14 into the space between the end flanges of the carrier, thence through ports 24 and 22 to the space between flange 6 of the piston and the next adjacent flange of the valve-carrier, and thence into the exhaust-port 2 of the piston-cylinder. For the broader purposes of my invention, however, the valve could be rigid or integral with the sleeve or otherwise suitably formed to slide on the piston and provided with end flanges for the general purpose for which the flanges 16 on sleeve E are provided, and as the feature of a spool-shaped piston provided with a pair

of end flanges and having a spool-shaped sleeve adapted to form a valve and arranged to work between the flanges on the piston 70 has been described in the art, illustration of such appears unnecessary.

What I claim as my invention is—

1. An engine comprising in combination a piston-cylinder provided with inlet and exhaust ports; a piston provided with end flanges or heads and an annular flange between the same, and having longitudinally-extending supply and exhaust ports or ducts extending back from its ends and opening outwardly 80 and laterally through its body portion, and further having an exhaust-space in a portion of its length and an exhaust port or duct extending back from such space and opening outwardly and laterally through its body portion; and a ported slide-valve arranged to control said ports and comprising a body portion having end flanges, substantially as described.

2. In a fluid-pressure engine, a reciprocating double-spool-shaped piston having one portion of its length provided externally with a flat slide-valve and the remaining portion of its length reduced to provide an exhaust-space; the piston being provided with supply and exhaust ports controlled by the valve and arranged to deliver fluid-pressure to and exhaust from opposite ends of the piston, and to conduct the exhaust to said exhaust-space, substantially as described.

3. The combination of a piston-cylinder provided with supply and exhaust ports; a reciprocating piston provided with suitable ports or ducts and having a portion of its length adapted to provide an exhaust space 105 or chamber; and a slide-valve arranged to work upon the remaining portion of the length of the piston and governing the supply and exhaust to and from the piston-cylinder at opposite ends of the piston, substantially as 110 described.

4. An engine comprising a piston having a portion of its length reduced to provide an exhaust-space and having a longitudinally-arranged bore forming an exhaust-port which 115 extends back from such exhaust-space and opens outwardly and laterally through the piston; and a slide-valve arranged to control such exhaust-port, substantially as described.

5. A fluid-pressure engine comprising in 120 combination a piston-cylinder having supply and exhaust ports; a piston having a portion of its length providing pressure-space to which fluid-pressure is delivered from the supply-port, and having the remaining portion of its length providing an exhaust-space 125 which communicates with the exhaust-port of the piston-cylinder; and a self-adjustable slide-valve arranged externally upon the piston and subject to pressure within said pressure-space; the valve and piston being ported to exhaust fluid-pressure from the pressure-space prior to the shift of the valve so as to lessen pressure upon the valve.

6. In an engine the combination of a piston-cylinder provided with supply and exhaust ports; a reciprocating piston having along a portion of its length an exhaust-space, 5 and having the remaining portion of its length provided with a pressure-space and ported to deliver pressure from the pressure-space to opposite ends of the piston and to deliver the exhaust to the exhaust space or chamber; and 10 a slide-valve arranged to work upon the piston and to control the ports in the same, substantially as described.

7. The combination of a suitably-ported double-spool-shaped piston having annular 15 end flanges or heads and an intervening annular flange and a flat slide-valve controlling the ports which open between one head and the middle flange of the piston; the portion 20 of the piston between such flange and its remaining head being suitably reduced to form an exhaust-space, substantially as described.

8. A fluid-pressure engine comprising a piston-cylinder provided with supply and exhaust ports; a reciprocating piston having 25 along a portion of its length an exhaust space or chamber in constant communication with the exhaust-port of the piston-cylinder, and having the remaining portion of its length provided with a pressure space or chamber, 30 and ported to deliver pressure from the pres-

sure-space to opposite ends of the piston and to deliver the exhaust to the exhaust space or chamber; and a slide-valve actuated by pressure admitted to the pressure-space which latter is, at the end of the stroke of the piston 35 one way, brought into communication with the exhaust-port of the piston-cylinder to exhaust pressure from a point opposite one end of the valve, substantially as described.

9. In an engine the combination, for the 40 purpose described, of the piston-cylinder having ports 1 and 2, of the piston constructed with heads 4 and 5, a middle flange 6, body portions 11, an exhaust-port 9, and supply and exhaust ports 7 and 8; and a valve by 45 which said ports are controlled, substantially as described.

10. The piston having a suitably-ported body portion provided with a head at one end and an annular flange at its opposite end, and 50 having a plate secured to said flange and connected with a head by separated body portions having ports or ducts; and a slide-valve by which the ports are governed, substantially as described.
